UNITED STATES PATENT OFFICE.

IRA S. DOWNING, OF INDIANAPOLIS, INDIANA, ASSIGNOR TO CAMEL COMPANY, A CORPORATION OF MAINE.

CAR-DOOR.

1,374,494.

Specification of Letters Patent. Patented Apr. 12, 1921.

Application filed July 10, 1919. Serial No. 309,978.

To all whom it may concern:

Be it known that I, IRA S. DOWNING, a citizen of the United States, residing at Indianapolis, in the county of Marion and 5 State of Indiana, have invented certain new and useful Improvements in Car-Doors, of which the following is a specification.

The invention relates to car doors and more particularly to freight and grain car doors and has for its principal objects; the provision of a car door that is strong, durable and inexpensive; the provision of a car door that may be required without necessitating its removal from the car should any 10 of its slats become broken or worn out; the provision of a car door that may conveniently be provided with an opening at any desired location for the purpose of ventilation; the provision of a car door that may 15 be easily and quickly converted into a grain door without necessitating a special car construction, the provision of a car door whereby grain or other products of like nature may be loaded through an opening in the 20 door which may afterward be closed with little difficulty, and such other objects as may hereinafter appear. Certain embodiments of my invention are shown in the accompanying drawings, wherein— 25

30 Figure 1 is an elevation of the inside face of the car door. Fig. 2 is a side elevation of the door shown in position on a car, the car portion being sectioned. Fig. 3 is a transverse section of the door and a portion 35 of a car taken on the line III—III of Fig. 2. Fig. 4 is a section through the frame portion of the door on the line IV—IV of Fig. 1. Fig. 5 is a section through the frame portion of the door on the line V—V 40 of Fig. 1. Fig. 6 is a section of the top of the frame portion of the door on the line VI—VI of Fig. 1. Fig. 7 is a section through the car floor adjacent the door showing a portion of a modified form of 45 door frame used with a packing strip. Fig. 8 is a section through the door post of the car showing a modified form of door frame used with a packing strip. Fig. 9 is a side elevation of a car showing the preferred 50 form of door in closed position on a car. Fig. 10 is an inside face view of a modified form of car door. Figs. 11 and 12 are bottom end and side elevations, respectively, of the door shown in Fig. 10. Fig. 13 is

an inside face view of another modification 55 of a door. Figs. 14 and 15 are side and top end elevations respectively of the door shown in Fig. 13, and Fig. 16 is a section on the line XVI—XVI of Fig. 13.

Referring to Figs. 1, 2 and 3 of the drawings, the door comprises a marginal frame made up of four malleable iron channel shaped sections, *i. e.* a bottom section 1, side sections 2 and 3 and a top section 4. The ends of the sections are mitered and 60 are joined together by means of diagonally disposed brace plates 5 which extend from the corners to a common central plate 6. The plates 5 are securely riveted to the sections at the corners thereby holding the sections together and the other ends of the plates 5 are securely riveted to the central 65 plate.

In addition to the brace plates 5 there are two plates 7 and 8 disposed on opposite 70 sides of the frame at the center thereof and which are riveted to the side frame sections 2 and 3.

The inside face of the frame sections is depressed at 9, Figs. 1 and 3, and the thickness of the plates 5 and 7 is such that all 75 brace plates are flush with the inside face of the door frame sections. The construction of frame sections and the manner of diagonally bracing them results in a very 80 rigid structure that cannot be distorted even by abnormally rough service.

The frame sections 1, 2, 3 and 4, being 85 channel shaped provide a recess or channel having the opening along the inner edge of 90 the frame sections. The purpose of the channel or recess is to support a plurality of either wood or metal slats which are passed into the channeled door frame through an opening 12, Fig. 2, provided 95 near the top of the outer edge of the frame section 3. The slats are inserted through the opening 12, one at a time, and allowed to slide to the bottom of the frame, the first one resting in the recess of the bottom 100 section 1 while the remainder rest on one another, until the frame is completely filled with slats. The ends of the slats are retained in the recess of the frame sections 2 and 3.

It is sometimes desirable to replace a slat due to injury or other failure, in which event, if the slat to be removed is near

the bottom it is cut or sawed so that it may be removed and the slats above let down. A new slat may then be inserted through the opening 12 near the top of the 5 frame.

Where ventilation of the car is desired the top slat may be removed and a slat or two moved upward, leaving a ventilating space such as at 13, Fig. 1. The slat 11^a is 10 then supported by means of the filler blocks 14, Figs. 1, 2 and 5. These blocks are provided with a screw 15, the head of which is adapted to slip through the key hole slot 16, and be retained by the narrow portion 15 of the slot. By arranging a plurality of key hole slots, filler blocks 14 may be placed at any desired position and as many ventilation spaces provided as is considered necessary.

20 The opening 12 is placed on the edge of the door adapted to be engaged by the door stop 17, Figs. 3 and 9, when the door is in closed position, as in Fig. 9. This arrangement, which closes the opening 12 when the 25 door is closed, prevents the removal of slats when the door is closed which is a very desirable feature. When the door is open there is sufficient clearance space to permit of the removal or replacing of slats without 30 the least inconvenience.

When it is desired to load grain into a car through the door, a slat is removed near the top of the door to permit the insertion of the grain chute. At such time the door is 35 in closed position and ordinarily the slat removed could not be replaced when the car was filled on account of the door stop covering the opening 12. To provide for this contingency, the door stop is made in two 40 pieces, (see Fig. 9), the top section 18 being detachable and is removed while the car is being filled with grain. When the car has been filled the slat which had been removed to permit of the insertion of the grain chute 45 is replaced and the stop section 18 then bolted and locked in place by any suitable means.

In order that the door may be used to hold grain without the use of the usual grain 50 door, the metal frame sections 1, 2 and 3 are provided with grooves 19 on their inner faces, that is, the side of the frame sections adjacent the car. When the door has been closed, packing strips 20 are inserted in the 55 grooves 19 and engage a seat 21 on the car floor and the car door posts. After the strips 20 have been positioned binding plates 22 are screwed to the floor and car door posts to retain the packing strips. Thus it 60 will be seen that no grain can leak out between the car door and the car.

Figs. 7 and 8 show modified forms of 65 frame sections with different shaped slots for the binding strips, wherein—Fig. 7 shows a bottom section 1' of the modified

form of door, and Fig. 8 shows a modified form of the side section 3'. Section 1' is provided with an undercut ridge 23 adapted to be engaged by a triangular shaped packing strip 24 which is screwed or nailed 70 to the car floor. The side frame section 3' shown in Fig. 8 of such modified form of door is provided with an undercut vertical groove 25, and the car door post is provided with an undercut vertical groove 75 26. Short pieces of packing strip 27 are then inserted near the top of the door and slid to the floor, the pieces being inserted until the packing is the desired elevation. Both methods of packing the door are very 80 simple and effective.

Referring to Figs. 10, 11 and 12, a modified form of door is shown, wherein the slats are arranged vertically instead of horizontally, in which case the opening 28, provided for the insertion and the removal of slats, is placed in the bottom frame member 29, the door rail of the car serving to close the opening when the car is in closed position.

90 Figs. 13, 14, 15 and 16 show a door having horizontal slats and a modified form of frame section. In this structure the sections are mortised at their ends so that the top and bottom sections 30 and 31, respectively, overlap the ends of the side sections 32 and 33. The diagonal brace plates 34 are riveted at one end to the corner of the frame and at the other end to the center of the cross plate 35. The construction is very rigid and durable. The horizontal slats are inserted through the opening 36 in the upper end of the outside edge of the side sections.

95 Where the horizontal slats are used it is desirable to ship lap the slats in a manner 105 to shed water readily, various form of lapping being shown in Figs. 4, 6 and 16.

I claim:

1. A sliding car door comprising an open frame, opposing slideways in said frame, a 110 slot in one of said slideways, opening substantially at right angles thereto, and a plurality of slats adapted to be successively passed endwise through said slot into the frame and then moved in opposing slide- 115 ways out of alignment with the slot, the ends of the slats fitting the slideways whereby the slats are held within the frame.

2. A car door comprising a frame, channels at the inner edges of the frame, a plurality of slats slidably mounted in the channels, slat spacing members adapted to fit into the channels, and means in the channels for supporting the spacing members, said spacing members serving to separate the 120 slats to provide an opening through the door.

3. The combination with a sliding car door having slats removable through an 125 opening in the vertical edge of the frame, of 130

a detachable door stop projecting from the side of the car and secured thereto adapted to cover the opening in the frame when the door is in closed position.

5 4. A car door comprising a frame made up of sections of channel shaped iron, the channels opening inwardly toward the center of the frame, stiffening members permanently securing the frame sections together, and counter sunk so that their outer face is flush with the face of the frame, and a plurality of slats slidably mounted in the frame adapted to fit the channels of the frame whereby they are retained within the

15 frame.

5. A sliding car door comprising a pair of frame members grooved to form slideways, a pair of end members terminally connecting said frame members to form a rigid frame, one of said grooved frame members being provided with a slot opening substantially at right angles into one of said slideways, and a plurality of slats adapted to be successively passed endwise through said

25 slot into the frame and then moved in the slideways out of alinement with the slot, the

ends of the slats fitting the slideways whereby the slats are held within the frame.

6. The combination with a door-way frame and its opening, of a car door mounted for sliding movement to occupy a position in said opening against said door-way frame, and comprising a pair of parallel frame members grooved to form slideways, a pair of end members connecting the ends 30 of said frame members to form a rigid door frame and terminally closing said slideways, one of said frame members having a relatively short portion thereof formed with a slot opening substantially at right angles 35 into one of the slideways, and a series of slats having their ends positioned in said slideways and their body portions disposed intermediate the end members, said slats constructed and arranged to be successively 40 passed endwise through the slot and then moved relatively of the door frame for positioning in the slideways, substantially 45 as described.

In testimony whereof I have hereunto signed my name.

I. S. DOWNING.

It is hereby certified that in Letters Patent No. 1,374,494, granted April 12, 1921, upon the application of Ira S. Downing, of Indianapolis, Indiana, for an improvement in "Car-Doors," an error appears in the printed specification requiring correction as follows: Page 1, line 13, for the word "required" read *repaired*; and that the said Letters Patent should be read with this correction therein that the same may conform to the record of the case in the Patent Office.

Signed and sealed this 17th day of May, A. D., 1921.

[SEAL.]

T. E. ROBERTSON,

Commissioner of Patents.
